UNITED STATES PATENT OFFICE.

HARRY E. DADE, OF MOUNT VERNON, NEW YORK.

BINDER AND LOCK THEREFOR.

SPECIFICATION forming part of Letters Patent No. 769,857, dated September 13, 1904.

Application filed June 8, 1898. Serial No. 682,870. (No model.)

To all whom it may concern:

Be it known that I, HARRY E. DADE, a citizen of the United States, residing at Mount Vernon, in the county of Westchester, State 5 of New York, have invented a new and Improved Binder and Lock Therefor, of which the following is a specification.

This invention relates to binders adapted to securely hold in book form a number of 10 movable sheets.

It also relates to a lock designed for and intended to be used in such binder, but also capable of uses in other relations.

The invention consists of the various features and combinations of features hereinafter referred to, and particularly specified in the 15 claims.

In the drawings forming part of this specification I have shown a binder and lock embodying the various features of my invention in the best form now known to me, showing also two of the many modifications of which the invention is susceptible.

Figure 1 is a sectional plan view of the 25 binder, taken on the line 1 1 of Fig. 2. Fig. 2 is a vertical section on the line 2 2 of Fig. 1. Figs. 3 and 4 are plan views of the upper binding-strip, parts being removed and showing certain parts in different positions. Fig. 5 is 30 a side elevation, partly in section, of a removable post. Fig. 6 is a horizontal section of the lock. Figs. 7 and 8 are views similar to Fig. 2, showing two different modifications. Figs. 9 and 10 are rear ends of two sheets 35 adapted for use in binders, including certain features of my invention.

Referring now to the various features comprising the invention, and particularly as shown in the accompanying drawings, A and 40 B designate two strips between which the sheets S are held in place. These strips are generally covered with leather or canvas and secured by suitable flexible connections or hinges to covers D. Between the strips A and B extends a pair of posts C and C, adapted to engage apertures, recesses, or shoulders formed in the sheets S at or near the margin thereof. These posts engage the strips A and B and in their best form are extensible, so as to

50 permit the strips to be separated within certain limits for the purpose of inserting additional sheets in place between them, as convenience may require, and also to permit the sheets already in the binder to be separated for the extraction of old sheets and the insertion of 55 new ones. In making the posts C extensible I prefer to construct them of two telescoping members, the male member engaging, as by a permanent rigid engagement, one of the strips and the farther end of the female member engaging the other strip permanently and rigidly, as shown in Fig. 2, or loosely, as shown in Figs. 7 and 8, as will hereinafter be described. As shown in Figs. 1 and 2, the male members a are in engagement with the strip 60 B and the female members b are in engagement with the strip A. To prevent the complete disconnection of the strips A and B, I may form heads c on the members a larger than the restricted openings d at the lower 65 ends of the members b, or other suitable means to accomplish this purpose may be employed.

Another feature of my invention is the removable post E, of which I prefer to employ two, extending through an aperture in one 70 strip, as A, and into engagement with the other strip, as B. These posts may vary considerably in their construction and arrangement. I prefer to have them engage the strip B by telescoping with short studs e, fixed to 75 said strip, and also to provide them with heads f, larger than the aperture e' in the strip A, so as to support these posts in proper position and prevent them from dropping down 80 too far. In using the removable posts E and 85 the non-removable posts C, I prefer to employ with them sheets, such as S, having closed apertures c' for the removable posts E and open apertures c² for the non-removable posts C, and when removing such a sheet from 90 the binder the posts E are first withdrawn, and the sheets being then free at the apertures c' may be pulled off the posts C, which at the open apertures c² do not form an impassable obstruction.

95 It is desirable to lock the posts E in place, so that the sheets may not be withdrawn from the binder except by the proper person. To

provide for this, any suitable device may be employed to engage the posts E. I prefer to use the device shown in the drawings, especially in Figs. 3 and 4. The strip A, as shown in these figures, and, in fact, in all the figures, is made in the form of a casing preferably of metal and has a top piece g secured in place by screws passing into bosses g^2 . Within the casing are slides F, connected by pivoted arms h to a rotatable button G, which is centrally located in the casing, the slides being supported on narrow flanges h' on the side walls of the casing. When the button G is rotated in one direction, the slides engage notches f' , cut in the heads f of the posts E, and thereby secure the posts in place. When the button G is reversed, the slides are withdrawn from the notches f' and the posts may be removed. The button G is preferably rotated by a key passing through a keyhole g^3 in the casing and into a slot g' in the button G. In order to render the posts readily removable by hand and at the same time keep the heads flush with the top of the strip A, I secure suitable springs beneath the heads f , which may be the small coiled springs f^2 , secured to the posts, which when the posts are in place rest upon the strip A and tend to lift the heads f above the top of the strip, so that they may be readily grasped by the hand. When the posts are held down in place, the springs f^2 sink into countersunk recesses f^3 in the bottom of the heads f . When the posts E have been passed down through the strips A, the springs f^2 hold the heads slightly above the top g of the strip, as has been explained, and in order to conveniently press the heads f down flush with the top g , so that the slides F may lock them there, I form a bevel on the lower side of the notches f' , whereby the slides themselves as they move outward contact with the bevels and automatically force the posts fully home.

In order to hold the strips A and B firmly against the sheets placed between them, and thereby prevent the removal of any sheet even when the posts E are omitted, as in some cases might be done, I employ means for locking the strips together, such means shown in the drawings being novel and one of the features of my invention whether considered by itself or in connection with other features. I prefer in all cases to employ this particular form of locking means; but if other locking means were used with my binder instead some of the features of my invention and their attending advantages would still be present. My locking device comprises a post extending between the strips A and B and having two members provided with interlocking faces, one at least of the members being rotatable with respect to the other, whereby the interlocking faces may be shifted into and out of engagement by the rotation of such member.

In the preferred embodiment of this device as shown in the drawings, J is such a post, comprising two members j and j' , the former being fixed to the strip B and the latter being rotatably connected with the strip A. The member j' is in the form of a tube having its bore provided with screw-threads j^3 , planed smooth on opposite faces of the bore. The member j is in the form of a post having quarter screw-threads j^2 and made smooth between these threads. The members j and j' may slide one in the other when their threads are out of mesh; but when the member j' is turned a quarter of a revolution the threads are fully in mesh and the members are locked together. The screw-threads thus form interlocking faces. By extending the member j a substantial distance into the member j' the post J is made extensible, whereby the strips A and B may be moved to and from each other and locked at various points of their separation. To prevent the members from being detached from each other, a head j^4 may be formed on the member j , which is unable to pass the threads j^3 when the members are unlocked. The member j' is preferably provided with a head adapted to receive a key for the rotation of said member. In employing this locking-post in the binder the button G serves as this head, and the member j' is secured to this button G. By this arrangement the locking-post may be operated simultaneously with the slides F and the parts be so arranged that the slides engage the posts E simultaneously with the locking of the lock. This arrangement is preferred and is that shown in the Figs. 1, 2, 3, and 4.

In order to prevent access to the locking-post J except at its end by means of the key and also in order to protect the ends of the sheets from dust and present a neat appearance, I employ a back for the binder, comprising two overlapping pieces K and K', secured to the outer edges of the strips A and B. These pieces K and K' are preferably secured to lugs h and h' , respectively, formed on the strips. To prevent the strips A and B from being entirely disconnected, I may connect the pieces K and K' by pins l and slots l' .

In a binder of the general character herein described wherein posts are employed to hold the sheets in place between the strips it may be observed that the sheets may be thus held in place with a certain degree of advantage and for some purposes by the employment of only two posts engaging apertures, notches, or shoulders formed in the sheets on the rear margin or at the two side margins near the rear. My binder in its preferred form, however, has five posts, including the locking-post J, as shown in Figs. 1, 2, 3, and 4. In such preferred form the locking-post J is not recommended to be used to engage apertures, notches, or shoulders in the sheets, so as to

thereby hold the sheets, as do the other posts, as such use in this form is unnecessary. The sheets are merely cut away to accommodate the locking-post J in order that they may be secured by the other sheet-posts; but it will be readily seen that the locking-post J could be employed as a sheet-post, if desired, by simply providing the sheets with apertures, notches, or shoulders therefor. In view of these facts it will be seen that some of the advantages of my invention may be secured in a binder useful for some purposes if of the five posts preferably employed by me, including the post J, any two or more were used as sheet-posts. If two of the posts J or one of them with one other post or any two other posts should be used alone to retain the sheets, it would be recommended to locate these posts somewhat near the ends of the strips A and B and omit the other posts; but this location would not be essential.

If the post J and one of the posts E should be used alone, one slide F would of course be omitted. The various other ways of using only certain features of my invention are so readily apparent upon suggestion that further explanation is deemed not necessary and would perhaps only serve to burden the case. In Fig. 8, however, I have shown a binder in which only three posts are employed, the locking-post J being used as a sheet-post or not, as desired.

Fig. 7 and Fig. 8 embody other modifications now to be described. In Fig. 7 is shown a binder identical in construction and use with that shown in Figs. 1, 2, 3, 4, and 5, except that the non-removable posts are not rigidly secured to the strip A, but are in loose engagement therewith, means being provided to secure them to the strip when the locking-post is unlocked. These posts are designated M and comprise the members m and m'. The members m have heads n fitting loosely in apertures or recesses p in the strip A and are provided with notches n', arranged to be engaged by catches n'', carried by the slides F', which, with the exception that they have catches n'', are similar to the slides F of Fig. 2. When the slides engage the removable posts E and the interlocking faces of the post J are in engagement, the catches n'' are out of engagement with the heads n, and when the interlocking faces of the post J are disengaged and the removable posts are free the catches n'' engage the heads n. It will thus be seen that when the strips A and B are moved apart for the insertion or withdrawal of sheets the members m will be carried by the strip A, so as thereby to extend the posts M. o is a pin secured in the head n of each post M and fitting notches in the recesses p, so as to insure the heads being properly centered in the recesses p for the catches n'' to enter the notches n'.

In Fig. 8 the posts E are omitted, and the

posts M have the notches n' turned toward the post J. The slides F', substantially similar to the slides F, engage these notches when the members of the locking-post are disengaged, the catches n'' being omitted.

70

In Figs. 9 and 10 are shown the rear ends of two sheets R and T. Side notches r and a back open aperture s are formed in sheet R and side shoulders t and a back open aperture s are formed in sheet T. These sheets 75 may be used in connection with the construction shown in Fig. 8, the post J being used as a sheet-post as well as a locking-post, if desired, and engaging the open apertures s. They also indicate some of the ways a sheet 80 may be engaged by the different posts shown in the other figures.

It will be observed that in Fig. 2 the smaller ends of the posts C—i. e., the ends having the smaller diameter—are arranged at the bottom and that the smaller ends of the posts E are arranged at the top, considering the tubes e a part of the posts E, or, in other words, the smaller or male ends of one pair of posts are opposite the female or larger ends 90 of the other pair of posts. The apertures or notches in the sheets engaged by these posts are preferably made of such size that they fit the larger portions of the posts snugly, so as to leave no room for play. The apertures or 95 notches fit the smaller portions of the posts, of course, less snugly. It is desirable to keep the sheets at all times in substantially exact alinement, and by the relative arrangement of the posts described this is accomplished notwithstanding the fact that each post differs in diameter as to its different portions. This results from the fact that there are always at least two apertures or notches in each sheet held by the larger portions of 100 two of the posts, so that the sheets can have no play.

The heads of the posts E and the apertures in the strip A, which receive them, may be flattened on one side, as shown in Figs. 3 and 110 4, to insure the proper centering of the posts, so that the slides F will always engage their notches f'. In some cases the notches f' may be omitted and the apertures closed by the slides F or otherwise above the posts E to 115 hold them in place.

While I have herein shown and described the various features and combinations of features of my invention in their preferred forms, I wish it to be understood that my invention 120 is not limited to such specific forms.

Various modifications will readily suggest themselves to those skilled in the art adapted in a greater or less degree to secure some of the advantages of the various features and 125 combinations of features included within the scope of my invention.

What I claim as new, and desire to secure by Letters Patent, is—

1. In a binder, the combination of two strips 130

adapted to be moved to and from each other, one or more extensible sheet-engaging posts extending between the strips, a lock separate and distinct from said post or posts arranged 5 to permit the strips to be moved to and from each other and which locks them together at various points of their separation, and means connected with the lock for engaging the said post or posts and thereby locking said post or 10 posts in place.

2. In a binder, the combination of two strips adapted to be moved to and from each other, one or more extensible sheet-engaging posts extending between the strips, a lock separate 15 and distinct from said post or posts arranged to permit the strips to be moved to and from each other and which locks them together at various points of their separation, and means connected with the lock for engaging the said 20 post or posts simultaneously with the locking of the lock and thereby locking said post or posts in place.

3. In a binder, the combination of two strips adapted to be moved to and from each other, 25 one or more extensible sheet-engaging posts extending between the strips, a lock separate and distinct from said post or posts arranged to permit the strips to be moved to and from each other and which locks them together at 30 various points of their separation, and means connected with the lock for engaging the said post or posts simultaneously with the operating of the lock and thereby locking said post or posts in place.

35 4. In a binder, the combination of two strips adapted to be moved to and from each other, one or more extensible sheet-engaging posts extending between the strips, a lock separate and distinct from said post or posts comprising 40 an extensible post having two members respectively engaging the respective strips and thereby arranged to permit the strips to be moved to and from each other and which locks them together at various points of their separation, and means connected with the lock 45 for engaging said sheet-engaging post or posts and thereby locking said post or posts in place.

5. In a binder, the combination of two strips, two or more sheet-engaging posts extending 50 between said strips of which at least one post is non-removable and one post is removable, the removable post extending through an aperture in one strip into engagement with the other strip, and means for securing said removable post in position.

6. In a binder, the combination of two strips adapted to be moved to and from each other, two or more sheet-engaging extensible posts extending between said strips of which at least 60 one post is non-removable and one post is removable, the removable post extending through an aperture in one strip into engagement with the other strip, and means for securing said removable post in position.

65 7. In a binder, the combination of two strips

adapted to be moved to and from each other, two or more sheet-engaging extensible posts extending between said strips of which at least one post is non-removable and one post is removable, the removable post extending 70 through an aperture in one strip into engagement with the other strip, and means for securing said removable post in position and means for locking the strips together at various points of their separation. 75

8. In a binder, the combination of two strips adapted to be moved to and from each other, two or more sheet-engaging extensible posts extending between said strips of which at least one post is non-removable and one post is 80 removable, the removable post extending through an aperture in one strip into engagement with the other strip, means for securing said removable post in position, and means comprising an additional extensible post having two members provided with interlocking faces and respectively engaging the respective strips whereby the removable post or posts may be secured in position and the strips locked together at various points of their separation. 85

9. In a binder, the combination of two strips adapted to be moved to and from each other, two or more sheet-engaging extensible posts extending between said strips of which at least 95 one post is non-removable and one post is removable, the removable post extending through an aperture in one strip into engagement with the other strip, means for securing said removable post in position, and means 100 comprising an additional extensible post having two members provided with interlocking faces and respectively engaging the respective strips, one of said members being rotatable with respect to the other, whereby the removable post or posts may be secured in position and the strips locked together at various points of their separation. 105

10. In a binder, the combination of two strips, two or more posts extending between 110 said strips of which at least one post is non-removable and one post is removable, the removable post extending through an aperture in one strip into engagement with the other strip, and having a lifting-spring and provided at its head with a bevel, and a slide adapted 115 to engage the bevel to force said post against the lifting-spring and secure it in position.

11. In a binder, the combination of two strips adapted to be moved to and from each other, a pair of sheet-engaging extensible non-removable posts and a pair of extensible removable posts extending between the strips, said removable posts extending through apertures in one strip into engagement with the other strip, means for securing said removable posts in position, and a lock for securing the strips at various points of their separation. 125

12. In a binder, the combination of two strips adapted to be moved to and from each 130

other, a pair of sheet-engaging extensible non-removable posts and a pair of extensible removable posts extending between the strips, said removable posts extending through apertures in one strip into engagement with the other strip, key-operated devices for simultaneously securing the said removable posts in position, and a lock for securing the strips at various points of their separation.

13. In a binder, the combination of two strips adapted to be moved to and from each other, a pair of extensible non-removable posts and a pair of extensible removable posts extending between the strips, said non-removable posts each comprising two members one of which is fixed to one strip and the other of which is provided with a locking-head loosely engaging the other strip and said removable posts extending through apertures in one strip into engagement with the other strip, means for securing said removable posts in position, a lock for securing the strips at various points of their separation, and means for engaging the locking-heads of said non-removable posts and thereby securing them to the strip which they engage simultaneously with the unlocking of the lock.

14. In a binder, the combination of two strips, two or more posts extending between said strips of which at least one post is non-removable and one post is removable, a non-removable post comprising two members one of which is fixed to one strip and the other of which is provided with a head loosely engaging the other strip, and a removable post extending through an aperture in one strip into engagement with the other strip; means for securing said removable post in position; and means for engaging the head of said non-removable post and thereby securing said non-removable post to the strip which said non-removable post engages simultaneously with the releasing of the removable post.

15. In a binder, the combination of two strips, two or more posts extending between said strips of which at least one post is non-removable and one post is removable, a non-removable post comprising two members one of which is fixed to one strip and the other of which is provided with a head loosely engaging the other strip, and a removable post extending through an aperture in one strip into engagement with the other strip; means for securing said removable post in position; and means for engaging the head of said non-removable post and thereby securing said non-removable post to the strip which said non-removable post engages simultaneously with the releasing of the removable post, and means for locking said strips together including an extensible post having two members provided with interlocking faces and secured respectively to the respective strips.

16. In a binder, the combination of two strips adapted to be moved to and from each

other, a pair of sheet-engaging extensible posts extending between the strips, each post comprising two members, one member of each of said posts being fixed to one strip and the other member of at least one of said posts being in loose engagement with the other strip, and means for locking said last-mentioned member to the strip which it engages.

17. In a binder, the combination of two strips adapted to be moved to and from each other and provided with means for locking them together in any desired position, a pair of sheet-engaging extensible posts extending between the strips, each post comprising two members, one member of each of said posts being fixed to one strip and the other member of at least one of said posts being in loose engagement with the other strip, and means for locking said last-mentioned member to the strip which it engages.

18. In a binder, the combination of two strips, adapted to be moved to and from each other and provided with means to prevent their complete separation, a pair of non-removable extensible posts secured at their ends to the respective strips, a pair of removable posts arranged to extend through apertures in one strip and into engagement with the other strip, an extensible locking-post comprising two members secured at their ends to the strips and having interlocking faces, one of said members being rotatable with respect to the other and adapted to receive a key at its end through an aperture in the corresponding strip, whereby the locking-faces may be shifted into and out of locking position, locking-slides connected with the rotatable member of said locking-post and arranged to lock the removable posts in position when the locking-post is locked, and overlapping pieces secured to the rear edges of the strips thereby forming an expandable back for the binder and preventing the locking-post from being unlocked except by its key when the binder is full of sheets.

19. In a binder, the combination of two strips, adapted to be moved to and from each other and provided with means to prevent their complete separation, a pair of non-removable extensible posts, each comprising two members one of which is fixed to one strip and the other of which is provided with a locking-head in loose engagement with the other strip, a pair of removable posts arranged to extend through apertures in one strip and into engagement with the other strip, an extensible locking-post comprising two members secured at their ends to the strips and having interlocking-faces, one of said members being rotatable with respect to the other and adapted to receive a key at its end through an aperture in the corresponding strip, whereby the locking-faces may be shifted into and out of locking position, locking-slides connected with the rotatable member

of said locking-post and arranged to lock the removable posts in position when the locking-post is locked, said slides being provided with means for engaging the heads of the non-removable posts when the locking-post is unlocked, and overlapping pieces secured to the rear edges of the strips thereby forming an expansible back for the binder and preventing the locking-post from being unlocked

except by its key when the binder is full of 10 sheets.

In testimony whereof I have signed my name to this specification in the presence of two subscribing witnesses.

HARRY E. DADE.
